UNITED STATES PATENT OFFICE.

FRANK P. REIDHAAR, OF CONNERSVILLE, INDIANA.

CONCEALED HINGE.

1,072,774.

Specification of Letters Patent.

Patented Sept. 9, 1913.

Application filed April 22, 1913. Serial No. 762,756.

To all whom it may concern:

Be it known that I, FRANK P. REIDHAAR, a citizen of the United States, residing at Connersville, in the county of Fayette and State of Indiana, have invented certain new and useful Improvements in Concealed Hinges, of which the following is a specification.

My invention relates to hinges, and has particular reference to concealed or partly concealed hinges which are particularly well adapted for use in connection with automobiles, to connect the doors with the bodies thereof, whereby upon the opening of the doors, the sagging of the same is prevented.

An important object of this invention is to provide hinges of the above mentioned character, which are adapted to be connected with the door of an automobile and so constructed that the door (the body of the automobile adjacent the door opening being laterally or vertically inclined and serving as a door jamb whereby the same is connected with the hinges) will have its upper end horizontally arranged when swung to the open position.

A further object of this invention is to provide a hinge of the above mentioned character, which is simple in construction, cheap to manufacture, strong and durable.

Other objects and advantages of this invention will be apparent during the course of the following description.

In the accompanying drawings, forming a part of this specification, and in which like numerals are employed to designate like parts throughout the same, Figure 1 is an inner side view of the hinges, showing the same in use, Fig. 2 is an outer side view of one hinge, Fig. 3 is an edge view of the door and hinges with the door in its open position, Fig. 4 is a horizontal sectional view taken on line 4—4 of Fig. 1, Fig. 5 is a detailed section taken on line 5—5 of Fig. 4, and, Fig. 6 is a similar view taken on line 6—6 of Fig. 1.

In the drawings, wherein for the purpose of illustration is shown a preferred embodiment of my invention, the numeral 7 designates the side or body of an automobile and the numeral 8 designates an outwardly swinging door. The body 7 has its portion 9 adjacent the door opening serving as a door jamb. The body 7 and the door jamb 9 are inclined from the vertical, as clearly shown in Fig. 3. Particular attention is

called to the fact that the door jamb 9 is inclined from the vertical, while in some automobile bodies the door jambs are vertically arranged, which is obtainable by having the side wall of the body forced or bulged outwardly. By the employment of my hinges it is unnecessary to have the door jamb vertically arranged, which has been found to add considerably to the cost of the manufacture of the automobile body.

The door jamb 9 is provided with upper and lower openings 10 for receiving the outer casings 11, which are U-shaped and have their inner sides open and their outer sides closed by means of plates 11^a, as shown. These U-shaped casings are provided at their ends with outwardly extending flanges 12, which are rigidly connected with the door jamb 9 by means of screws 13 or the like, as more clearly shown in Fig. 3. Adapted for insertion within the outer casings 10 are inner casings 14, comprising side strips 15. The inner ends of the side strips 15 in each casing 14 are rigidly connected by a stationary pin 16, provided with a conical portion 17 increasing in diameter downwardly and arranged eccentrically with relation to the ends of the pin 16, as more clearly shown in Fig. 6. The conical portion 17 extends transversely of the strips 15 toward their outer longitudinal edges. The side strips 15 are provided at their outer ends with outwardly extending flanges 18, fitting within sockets 19 formed in the flanges 12. The flanges 18 are held in place by screws 20 or the like. It is thus seen that each inner casing 14 may be removed from the casing 10 without disturbing the latter.

Each hinge further comprises a U-shaped arm 21, one end of which is countersunk into the edge of the door and rigidly connected therewith by means of screws 22 or the like. The opposite end of the U-shaped arm 21 is provided with an enlarged head 23, having a conical opening 24 formed therethrough for receiving the conical portion 17 of the pin 16. The upper and lower hinges are identical, except that the lower hinge is made suitably larger, the pin 16 of the lower hinge being arranged a greater distance from the adjacent edge of the door 8 than the pin 16 of the upper hinge.

As clearly shown in Fig. 2, the U-shaped arms 21 and associated elements are completely concealed from exterior view when

the door 8 is closed. When the door 8 is closed, the head 23 carried by the arm 21 is inclined from the vertical to have its longitudinal axis parallel with the longitudinal axis of the door jamb 9 which is transversely inclined from the vertical, but, as shown in Fig. 3, when the door is moved to its open position, the head 23 is swung in a vertical plane transversely of the longitudinal axis of the door jamb 9, whereby its longitudinal axis will be vertically arranged and disposed at an angle to the longitudinal axis of the door jamb 9. In this manner the head 23 and arm 21 carried thereby, are swung in a vertical plane transversely of the body 7, to maintain the door horizontal when moved to its open position.

It is to be understood that the form of my invention herewith shown and described, is to be taken as a preferred example of the same, and that certain changes in the shape, size and arrangement of parts may be resorted to without departing from the spirit of the invention or the scope of the subjoined claims.

Having described my invention, I claim:—

1. In a hinge of the character described, the combination with a casing to be mounted upon a door jamb which is inclined from the vertical, of an arm to be connected with a door, means pivotally connecting the arm with the casing and adapted to automatically swing the arm upwardly while the same is being swung horizontally toward its open position, and means concealing the several parts of the hinge from an exterior view.
2. In a hinge of the character described, the combination with a casing to be mounted upon a door jamb which is inclined from the vertical, of an arm to be connected with a horizontally swinging door, and means

pivots connecting one end of the arm 45 with the casing so that the arm will have its upstanding axis parallel with the upstanding axis of the door jamb when the door is closed and its upstanding axis inclined from the vertical and arranged at an 50 angle to the upstanding axis of the door jamb when the door is moved to the open position.

3. In a hinge of the character described, the combination with a casing having one 55 side closed and its opposite side open, of a pin mounted within the casing and rigidly connected therewith and having its longitudinal axis parallel with the upstanding axis of the casing, said pin being provided 60 with a conical portion which increases in diameter downwardly and is eccentrically arranged with relation to the longitudinal axis of the pin, and an approximately U-shaped arm to be attached to a door and 65 carrying a head having a conical opening to receive the conical portion of the pin.

4. In a hinge of the character described, the combination with a pin provided with a conical portion which is eccentrically arranged with relation to the longitudinal axis of the pin, means rigidly connecting the pin with a door jamb of an automobile body so that the longitudinal axis of the pin is parallel with the longitudinal axis 75 of the door jamb and the conical portion of said pin extends outwardly and transversely of the door jamb, and an arm to be connected with a door and carrying a head provided with a conical opening for receiving the conical portion of the pin.

In testimony whereof I affix my signature in presence of two witnesses.

FRANK P. REIDHAAR.
